US0D1028914S

(12) **United States Design Patent** (10) Patent No.: **US D1,028,914 S**
 Belcastro et al. (45) Date of Patent: ** May 28, 2024

(54) **DUAL CABINET HIGH DENSITY POWER DISTRIBUTION UNIT**

(71) Applicant: **ABB Schweiz AG**, Baden (CH)

(72) Inventors: **Christopher Alan Belcastro**, Mechanicsville, VA (US); **Gilbert Taylor Miller**, Henrico, VA (US)

(73) Assignee: **ABB SCHWEIZ AG**, Baden (CH)

(**) Term: **15 Years**

(21) Appl. No.: **29/777,086**

(22) Filed: **Apr. 2, 2021**

(51) LOC (14) Cl. **13-03**

(52) U.S. Cl.

(57) **CLAIM**

The ornamental design for a dual cabinet high density power distribution unit, as shown and described.

DESCRIPTION

FIG. 1 is a front side perspective view of a dual cabinet high density power distribution unit;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof; and,

FIG. 7 is a bottom side plan view thereof.

The broken lines shown in the figures are for the purpose of illustrating portions of the dual cabinet high density power distribution unit that form no part of the claimed design.

1 Claim, 5 Drawing Sheets
